(57) CLAIM

The ornamental design for a shaver package, as shown and described.

DESCRIPTION

FIG. 1 is a perspective view of a shaver package;
FIG. 2 is a top view of the shaver package of FIG. 1;
FIG. 3 is a front view of the shaver package of FIG. 1;
FIG. 4 is a right side view of the shaver package of FIG. 1;
FIG. 5 is a rear view of the shaver package of FIG. 1;
FIG. 6 is a left side view of the shaver package of FIG. 1; and,
FIG. 7 is a bottom view of the shaver package of FIG. 1.
The broken lines are shown for illustrative purposes only and form no part of the claimed design.
